SLUDGE HANDLING SYSTEM AND APPARATUS

Filed Aug. 19, 1946

UNITED STATES PATENT OFFICE

2,541,630

SLUDGE HANDLING SYSTEM AND APPARATUS

Charles Yeomans, Hubbard Woods, Ill., assignor to Yeomans Brothers Company, Chicago, Ill., a corporation of Illinois

Application August 19, 1946, Serial No. 691,606

11 Claims. (Cl. 210—2)

1 This invention relates to an improvement in gas displacement pumping systems such as are used for pumping sludge from a sewage settling tank to a digester, in which the sludge is decomposed to form a combustible gas which is stored under pressure and delivered to various gas consuming appliances.

This application is a continuation-in-part of my prior, co-pending application Serial Number 583,539, now Patent No. 2,481,894, which was filed on March 19, 1945, and which is assigned to the assignee of the present invention. Certain of the features of the present invention are directed to improvements in the pumping system disclosed in my co-pending application, and particularly, to improvements in the control equipment for systems of that type.

Heretofore in the pumping of sludge in digester gas producing systems it has been the practice to use reciprocating pumps for moving the sludge from the settling tank to the digester. This has given rise to serious problems in maintaining the pumping equipment in operable condition, because the materials handled made it necessary that the pumps be cleaned and the pump valves be reseated at frequent intervals. Such cleaning is not only an expensive, time-consuming operation, but it is also objectionable, because it subjects the workmen who do the cleaning to the dangers of serious illness or even asphyxiation due to back flow of gas from the digester. There is also the further danger that an explosive mixture of gas and air may be produced in the pump pits due to leakage of the gas from the line to the digester. Again, continuity of operation requires the costly provision of duplicate alternate pumping equipment, each unit of which may be placed in operation when the other is taken down for cleaning and adjustment.

Most of these difficulties can be overcome by the use of pneumatic, or gas displacement type, ejectors for this purpose. However, prior to the development of the system disclosed in my said co-pending application the use of gas displacement ejector equipment for this purpose has not been considered feasible because of the possibility that air from the ejector equipment will become mixed with the gas produced in the digester to form a highly explosive gas mixture.

As above stated, the present invention is an improvement of the system of my prior application. It provides an arrangement whereby a gas displacement ejector may be employed for the automatic pumping of sludge from a settling tank to a digester, or like operations, without incur-

2 ring any risk of producing an explosive mixture of air and gas in or about the system.

A particular object of the invention is to provide a sludge moving system which will be automatically operative for an extended period of time with a minimum of maintenance and other servicing, and which will, for these and other reasons, be exceptionally low in cost of operation and maintenance.

Other objects and advantages of the invention will be understood by reference to the following specification and accompanying drawings, wherein is illustrated an exemplary embodiment of the improved control method and apparatus.

In the drawings:

Fig. 1 is a diagrammatic illustration of the system and apparatus;

Fig. 2 is an enlarged detail sectional view of the ejector control rod stuffing box;

Fig. 3 is a diagrammatic sectional view of control valve 13.

In the operation of most sewage treatment plants, sludge and other materials are removed from the system by means of settling tanks or clarifiers, one of which is indicated at 11. The settling tank or clarifier 11 is equipped near its top with a peripheral trough forming weir 13. The heavy solid particles of sewage or sludge delivered into the tank settle to the bottom while the supernatant liquid flows over the upper edge of the weir 13 into a trough from which it is in turn conducted to other clarifying treatments or to a point of disposal.

Sludge is drawn from the bottom portion of the tank by an outlet pipe 15 which preferably extends from near the bottom of the settling basin to near the top thereof. The discharge end of the sludge outlet pipe, in conventional practice, is connected to the suction side of the pump which discharges the sludge through a suitable pipeline 31 into a digester 17. Usually the pump is located below the level of the bottom of the settling tank or clarifier to provide gravity flow to the inlet side of the pump. In the digester, the sludge is decomposed and a combustible gas (methane) is formed which is drawn off by a compressor 19 which delivers the gas under pressure, for example, 30 pounds per square inch, through a check valve 87 and pipeline 85 to a suitable gas holder 21. From the gas holder 21, the gas is conducted through a pipeline 23 to various appliances wherein the gas is used. The compressor 19 in the illustrated embodiment of the invention is motor driven and is controlled by an elec-

trical control system acting through an electrical starting unit 20.

According to the present invention, the sludge is conducted from the settling tank 11 into the receiver 25 of a gas displacement type ejector through a pipeline 26. The sludge enters the receiver through the inlet 27 communicating with the bottom of the receiver and it is discharged from the receiver through the outlet 29 which communicates through a pipeline 31 with the digester 17. Suitable uniflow check valves which may be of the flap type, as indicated at 33 and 35, are provided in the receiver inlet 27 and outlet 29 to prevent reverse flow of the sludge. Also, suitable valves, such as indicated at 37 and 39 respectively, are provided in the pipelines 26 and 31 for permitting closing thereof.

The receiver 25 has a top opening normally closed by a cover 41 which is equipped with a suitable stuffing box 42 through which there is 20 slidably mounted a shaft or rod 43 which actuates the ejector control means. The lower end of the rod 43 has connected to it downwardly and upwardly facing bells 45 and 47 respectively, which are spaced about as shown in the drawing, and so arranged that the weight of liquid in the lower bell will always tend to move the rod downwardly into the receiver while air or gas trapped in the downwardly facing bell when the level of the receiver contents reaches the lower edge thereof 30 will operate to lift the bell and move the rod 43 upwardly through said stuffing box.

It is desirable that the rod 43 be vertically movable without excessive binding by the stuffing box 42 which must be provided to prevent leakage of 35 gas from the receiver around the rod 43. To prevent the escape of gas without necessitating excessive tightening of the packing 40 around the rod 43, the arrangement illustrated in Fig. 2 is provided. As there shown, the packing gland 38 40 is provided with an annular shaped groove or chamber 44 around the rod 43 near the upper end of the gland. The chamber 44 communicates through a port 46 with a waste gas pipe 48, which is preferably vented to the atmosphere where the 45 liberation of gas will not create a hazard.

Above the chamber 44, the gland is provided with an auxiliary packing filled recess 50, which is closed by a pressure plate 52. The auxiliary packing in the recess 50 will, of course, be sufficiently tight around the rod 43 to prevent the passage of any gas from the chamber 44 upwardly around the rod. The contact area of the packing in the recess 50 is small as compared with the contact area of the packing 40, so that the auxiliary packing in the recess 50 will not afford an objectionable grip on the rod 43 to interfere with its vertical movement. At the same time it reduces greatly the pressure which must be applied to the main packing 40 to obtain a satisfactory 55 seal.

The upper end of the rod 43 is connected by means of a link 49 to the arm 51 of the bell crank lever, the other arm 53 of which is connected to the piston 55 of a three-way, piston valve 57. The valve 57 has one port 61 in communication with the interior of the receiver 25, another port 63 connected by means of pipelines 66 and 65 to the gas holder 21, and another port 67 connected by means of a pipeline 69 to the compressor intake 70 pipeline 71. Surges of pressure are not desirable in the digester 17 as the optimum operating pressure is approximately 8 inches of water. To prevent such surges when the receiver is vented, a check valve 79 is included in pipeline 71, allow-

ing flow only in the direction indicated by the arrow shown in the drawing.

The control system comprises a plurality of pressure responsive electrical switches and an electrical motor starting device 20 operable to energize the compressor 19, the system is energized by a source of electrical power entering the system by a line switch 78. A pressure responsive safety switch 91 is connected in series with the source of power and is designed to effect de-energization of the compressor upon the reduction of pressure in the digester to a predetermined critical value. The normally open pressure responsive switch 99 is designed to maintain the desired pressure in the gas holder 21. The normally open pressure responsive switch 28 serves to energize the compressor upon admission of compressed gas to pipeline 75. An alternative pressure control means is introduced by a pressure responsive switch 89 which serves to energize the compressor upon the increase of pressure in the compressor inlet line to a value greater than the critical pressure in the digester.

During normal operation of the gas producing system the line switch 78 is closed and the operation of the compressor is controlled by the pressure switch 99 so as to maintain the desired pressure within the gas holder by withdrawing gas from the digester. If the rate of gas withdrawal becomes excessive, the safety control switch 91 on the digester opens the circuit until the desired pressure is again reached. In order to start the operation of the ejector system, gas shut-off valve 101 is opened; the two position three-way valve 73 is opened so as to simultaneously admit gas under pressure from the gas holder 21 to the inlet valve port 63 and through pipeline 75 to the normally open pressure switch 28, which closes the circuit thus energizing the compressor 19; and, sludge valves 37 and 39 are opened. When the sewage level in the receiver reaches a predetermined high point the piston 55 of valve 57 will be moved from the position shown to the right-hand side of the valve opening intake port 63 and thus admitting compressed gas to the receiver. The gas being under pressure will force the sludge downwardly in the receiver and out through the discharge pipe 29 and through the pipeline 31 into the digester. When the sludge level is lowered sufficiently the weight of liquid in the bell 47 will restore the valve piston to the position shown, wherein the intake port 63 is sealed and the vent port 67 is opened. The gas trapped under pressure in the receiver will then escape through the vent port 67 and the pipeline 69 to the inlet side of the gas compressor, whereby the gas is re-compressed and forced through pipeline 85 and uniflow valve 87. As the vented gas discharged from the receiver is at a pressure of approximately 30 pounds per square inch, a uniflow check valve 79 is introduced into line 71 between the digester and the compressor. The valve 79 prevents a surge of pressure in the digester and the resultant rupture of the safety seal 81, thus venting the digester gas to the surrounding atmosphere. The sludge will then flow into the receiver through inlet 27 until bell 45, as before described, effects the admission of compressed gas, thus automatically restarting the pumping cycle.

In some cases it will be desirable to reduce the pressure more rapidly in the receiver than can be accomplished by the direct action of the compressor. In such cases an expansion tank 83 may be provided to absorb a portion of the pres-

sure from the vented compressed gas. The introduction of the expansion tank and the resulting rapid pressure decrease in the receiver upon venting facilitates the rapid filling of the receiver and, thus, increases the capacity of the ejector.

When it is desired to halt the pumping operation three-way valve 73 is turned so that pipeline 65 is blocked, thus effecting interruption of the flow of compressed gas to control valve 57. The passageways in valve 73 then vent the compressed gas in pressure responsive switch 28 and the receiver 25 through their appropriate pipelines, 75 and 66, to waste gas pipeline 93. The waste gas line contains a uniflow check valve 95 which permits flow in the direction shown by the arrow and thereby excludes air from the closed gas system. The reduction of pressure resulting from venting through line 93, returns pressure responsive switch 28 to its normally open position, and de-energizes the compressor 19. Shut-off valve 101 is then closed to insure exclusion of sludge from the control valve 57 by the action of the gas trapped in the receiver outlet port 61.

The use of a three-way control valve, such as valve 73, insures that both the operation of the ejector and the compressor are interrupted simultaneously, thereby preventing possible damage to equipment that might result from unattended operation.

If it is desired to reduce the operating time of the compressor, a normally open pressure responsive switch 89 may be incorporated into the inlet side of the compressor in place of pressure responsive switch 28. Switch 89 is so adjusted that the compressor operates when the pressure in line 14 rises above the pressure that is normally maintained in the digester (8 inches of water). The compressor will then operate until the pressure in the digester is reduced to 8 inches of water, at which point pressure responsive switch 91, a normally closed safety switch, opens, thus de-energizing the compressor. In this manner the compressor will be energized during periods of venting the receiver and will be de-energized during the ejection period of the operating cycle.

Other control devices incorporated into this system are a manually operated switch 97 and a pressure maintenance switch 99. The manually operated switch is designed to enable the operator to start the compressor and effect the collection of gas from the digester at any time desired. Pressure responsive switch 99 is a normally open switch designed to maintain pressure in the gas holder at about 30 pounds per square inch. When the demand of the gas burning appliances reduces the pressure in the gas holder the compressor automatically collects gas from the digester, thereby restoring pressure in the gas holder.

By employing the compressed gas from the gas holder for ejecting sludge from the receiver, there is, of course, no danger of creating an explosive air and gas mixture. Also, the arrangement involves no loss of gas since all of the gas used for expelling the sludge from the receiver is retained in the system by being returned to the digester from which it again flows through the compressor into the gas holder.

Means other than the described vertically movable bell arrangement may be employed for controlling the admission and relief of gas to and from the receiver. Such other means are well

known in the art as, for example, the electrode control for ejector systems disclosed in U. S. Patent No. 2,300,039, of which I am a co-inventor, or the combined float and electrical control system shown in my prior Patent No. 2,040,892. The described arrangement is intended only to represent a typical control means and it may be replaced by any of the well known alternatives which serve or are adaptable to the same purpose.

Sewage and materials other than sludge may be moved by the described apparatus, and the term "sludge" is used in the following claims merely to refer to the material moved rather than to limit the scope of the invention to the moving of that particular material.

The features of my invention that I believe to be new are expressly set forth in the following claims.

I claim the following as my invention:

1. In apparatus of the class described, a digester, a closed gas system for collecting and holding the gas produced in said digester, said system including a gas holder and a gas compressing unit operable to withdraw gas from said digester and deliver it under pressure to said gas holder, a gas displacement ejector which includes a receiver having inlet and outlet connections, means for conducting material to be moved by said ejector into said receiver through said inlet connection, means connecting said outlet connection to said digester, means operable to conduct gas under pressure from said holder to said receiver upon the occurrence of predetermined conditions to effect movement of material from said receiver to said digester, means operable, following each operation of said ejector, to return the gas to said gas compressing unit whereby said gas is recompressed and delivered to said holder, and means intermediate said compressing unit and said digester to prevent the return of gas under pressure to said digester.

2. In apparatus of the class described, a digester, a closed gas system for collecting and holding the gas produced in said digester, said system including a gas holder and a gas compressing unit operable to withdraw gas from said digester and deliver it under pressure to said gas holder, a gas displacement ejector which includes a receiver and ejector control means responsive to the level of material contained in said receiver to admit pressure gas to said receiver at the beginning of each ejection operation and to vent said receiver at the conclusion of each ejection operation, said receiver having inlet and outlet connections, means for conducting material to be moved by said ejector into said receiver through said inlet connection, means connecting said outlet connection to said digester, pressure responsive means operable to effect the energization of said compressor, and means including a valve operable to conduct gas under pressure from said holder to said ejector control means and simultaneously to said pressure responsive means, whereby said ejector becomes operable to move material into said digester, said ejector control means being operable following each operation of said ejector to return the compressed gas from said receiver to said compressor to be re-compressed and delivered to said holder without substantial dilution thereof, and means including a check valve intermediate said compressor and said digester to prevent the return of gas under pressure to said digester.

3. In apparatus of the class described, a di-

gester, a closed gas system for collecting and holding the gas produced in said digester, said system including a gas holder and a gas compressing unit operable to withdraw gas from said digester and deliver it under pressure to said gas holder, a gas displacement ejector which includes a receiver and control means responsive to the level of material contained in said receiver to admit pressure gas to said receiver at the beginning of each ejection operation and to vent said receiver at the conclusion of each ejection operation, said receiver having inlet and outlet connections, means for conducting material to be moved by said ejector into said receiver through said inlet connection, means connecting said outlet connection to said digester, pressure responsive means operable to effect the energization of said compressor valve means operable to conduct gas under pressure from said holder to said receiver and to said pressure responsive means thereby to effect the energization of said gas compressing unit and the movement of material from said receiver to said digester, control means operable to de-energize said compressor unit upon the reduction of pressure in the digester to a predetermined critical value, and means operable, following each operation of said ejector to return the compressed gas to said holder without substantial dilution thereof and without increasing pressure in the digester.

4. In apparatus of the class described, a digester, a closed gas system for collecting and holding the gas produced in said digester, said system including a gas holder and a gas compressing unit operable to withdraw gas from said digester and deliver it under pressure to said gas holder, a gas displacement ejector which includes a receiver and control means responsive to the level of material contained in said receiver to admit pressure gas to said receiver at the beginning of each ejection operation and to vent said receiver at the conclusion of each ejection operation, said receiver having inlet and outlet connections, means for conducting material to be moved by said ejector into said receiver through said inlet connection, means connecting said outlet connection to said digester, means operable to conduct gas under pressure from said holder to said receiver to effect movement of material from said receiver to said digester, means operable to energize said gas compressing unit upon the increase of pressure in the ejector gas exhaust system to a critical value, control means operable to deenergize said compressor unit upon the reduction of pressure in the digester to a predetermined minimum value, and means operable, following each operation of said ejector to return substantially undiluted gas to said holder without increasing pressure in the digester.

5. In apparatus of the class described, a digester, a closed gas system for collecting and holding the gas produced in said digester, said system including a gas holder and a gas compressing unit operable to withdraw gas from said digester and deliver it under pressure to said gas holder, control means therefor to maintain a predetermined pressure in said gas holder and means to prevent reduction of pressure in the digester below a critical value, a gas displacement ejector which includes a receiver having inlet and outlet connections, means for conducting material to be moved by said ejector into said receiver through said inlet connection, means connecting said outlet connection to said digester, means operable to conduct gas under pressure

from said holder to said receiver upon the occurrence of predetermined conditions to effect movement of material from said receiver to said digester, and means operable, following each operation of said ejector to deliver said substantially undiluted gas to the inlet side of said compressor, whereby said gas is delivered to said gas holder and means including a uniflow valve whereby substantially equal pressures are maintained in the digester.

6. In apparatus of the class described, a digester, a closed gas system for collecting and holding the gas produced in said digester, said system including a gas holder and a gas compressing unit operable to withdraw gas from said digester and deliver it under pressure to said gas holder, control means therefor to maintain a predetermined pressure in said gas holder and means to prevent reduction of pressure in the digester below a critical value, a gas displacement ejector which includes a receiver and control means responsive to the level of material contained in said receiver to admit pressure gas to said receiver at the beginning of each ejection operation and to vent said receiver at the conclusion of each ejection operation, said receiver having inlet and outlet connections, means for conducting material to be moved by said ejector into said receiver through said inlet connection, means connecting said outlet connection to said digester, pressure responsive means operable to effect the energization of said compressor, valve means operable to conduct the gas under pressure from said holder to said receiver and to said pressure responsive means, thereby to effect simultaneously the energization of said gas compressing unit and the movement of material from said receiver to said digester, and means operable, following each operation of said ejector to vent said receiver and to deliver the gas so vented to the inlet side of said compressor without substantial dilution thereof, whereby said gas is returned to said gas holder, and means including a uniflow valve whereby surges in the system resulting from the venting of said receiver are prevented from substantially changing the pressure normally maintained within said digester.

7. In a system of the class described, a gas producing digester, a gas displacement ejector including a receiver, having sludge inlet and outlet openings, a control device responsive to the level of material contained in said receiver for admitting compressed gas to said receiver at the beginning of each ejection operation and for venting said receiver at the conclusion of each ejection operation, and material conducting means for conducting sludge to the inlet of said ejector, means for conducting said sludge from the outlet of said ejector to said digester, and a closed gas system for collecting and holding the digester gas under pressure, said gas system including a gas holder, a gas compressor, an expansion tank connected to the inlet side of said compressor, the outlet of said compressor being connected, through a uniflow valve to said gas holder, the inlet side of said compressor and said expansion tank being connected to said digester through a uniflow valve, a pressure responsive safety control device connected to said digester and operable to de-energize said compressor upon reduction of pressure in the digester to a predetermined critical value, means for conducting gas vented from the outlet of said ejector by said ejector control device to said expansion tank, means for conducting compressed gas

from said gas holder to said ejector control device, said last mentioned means including a control valve operable to simultaneously admit compressed gas to said ejector control device and to a pressure switch which is operable to effect the energization of said compressor.

8. In a system of the class described a gas producing digester, a gas displacement ejector including a receiver, having sludge inlet and outlet openings, an ejector control device responsive to the level of material contained in said receiver for admitting compressed gas to said receiver at the beginning of each ejection operation and for venting said receiver at the conclusion of each ejection operation, and material conducting means for conducting sludge to the inlet of said ejector, means for conducting said sludge from the outlet of said ejector to said digester, and a closed gas system for collecting and holding the digester gas under pressure, said gas system including a gas holder, a gas compressor, the outlet of said compressor being connected, through a uniflow valve to said gas holder, the inlet side of said compressor being connected to said digester through a uniflow valve, a pressure responsive safety control device connected to said digester and operable to de-energize said compressor upon reduction of pressure in the digester to a predetermined critical value, means for conducting gas vented from the outlet of said ejector by said ejector control device to said gas compressor inlet, means for conducting compressed gas from said gas holder to said ejector control device, said last mentioned means including a control valve operable to simultaneously admit compressed gas to said ejector control device and to a pressure switch which is operable to effect the energization of said compressor.

9. In a treating system of the class described wherein material is delivered to a digester, in which a combustible gas is formed, and wherein such gas is compressed by a compressor and delivered to a gas holder for delivery to gas using appliances, the method of moving material into the digester which consists in delivering the material to be moved to the receiver of a gas displacement ejector, admitting compressed gas from the gas holder to said ejector receiver to effect movement of material from the ejector into the digester, and finally venting the ejector by returning the gas supplied thereto to said compressor, by-passing said digester.

10. In a sewage treating system wherein sludge is settled out in a settling tank and delivered to a digester, in which a combustible gas is formed, and wherein such gas is compressed by a compressor and delivered to a gas holder for delivery to gas using appliances, the method of moving sludge from the settling tank to the digester

5

10

which consists in delivering the sludge to be moved to the receiver of a gas displacement ejector by gravity flow from the settling tank to the receiver, admitting gas under pressure from said gas holder to said receiver to effect movement of sludge from the receiver into the digester, and finally venting the ejector receiver by returning the gas supplied thereto to said compressor for re-compression and re-delivery to said holder while simultaneously preventing the pressure gas vented from said ejector receiver from entering said digester.

15

11. In a sewage treatment system wherein sludge is settled out in a settling tank and delivered to a digester in which a combustible gas is formed, and wherein such gas is withdrawn from the digester by a compressor and compressed therein and delivered to a gas holder, the method of moving sludge from the settling tank to the digester which consists in delivering the sludge to be moved to the receiver of a gas displacement ejector having inlet and outlet openings, which openings are respectively connected to the settling tank and the digester, admitting gas under pressure from said gas holder to said receiver when sludge has filled said receiver to a predetermined level, said gas under pressure serving to effect movement of the sludge from the receiver through said outlet opening and into the digester, and finally venting the ejector receiver by returning the gas supplied thereto to said compressor while simultaneously preventing the back-flow of said returned gas into said digester, said venting occurring when the level of sludge in the receiver reaches a predetermined low level, thereby to permit sludge to again flow into the receiver.
